FLUID PRESSURE ACTUATED DEVICE

Ralph R. Gunderson, Detroit, Mich.

Application September 28, 1942, Serial No. 460,006

9 Claims. (Cl. 60—54.6)

The invention relates to fluid pressure actuated devices and refers more particularly to fluid pressure actuated devices of that type having fluid receiving chambers of different cross sectional pressure areas for exerting different pressures.

The invention has for some of its objects to provide an improved fluid pressure actuated device which is constructed to conserve the amount of fluid required to actuate the device and to increase the power output of the device during the second stage of its actuation without requiring a fluid pressure greater than that at the end of the first stage of its actuation; to provide a fluid pressure actuated device in which fluid under pressure flows to but one fluid receiving chamber at a time and the fluid receiving chambers of smaller and larger pressure areas are successively operable; and to provide a fluid pressure actuated device in which a simple valve mechanism controls the fluid under pressure to but one chamber at a time.

The invention has for other objects to provide a fluid pressure actuated device so constructed that it is effective in operation and may be economically manufactured; to provide a fluid pressure actuated device in which the fluid receiving chambers are formed by cylinders and a unit piston member and the unit piston member is slidably carried by the cylinders and normally held in predetermined relation to one of the cylinders; and to provide the piston member with a port intermediate its ends and passages extending through the pistons from the port to the cylinders and controlled by valves movable in unison.

These and other objects of the invention will become apparent from the following description, taken in connection with the accompanying drawing, in which

Figure 1 is a diagrammatic elevation illustrating a structure employing a fluid pressure actuated device embodying the invention;

Figure 2 is a longitudinal central section through a fluid pressure actuated device;

Figures 3 and 4 are cross sections on the lines 3—3 and 4—4, respectively, of Figure 2.

The fluid pressure actuated device is designed particularly for use in brakes for motor vehicles, although it is apparent that the device may be used in other structures. As illustrated particularly in Figure 1, the device is employed in a brake which may be of standard construction. In detail, the brake comprises the rotatable brake drum 1 and the non-rotatable friction elements 2 and 3 engageable with the drum. The friction elements are brake shoes pivotally mounted at corre-

sponding ends on the backing or carrier plate and operatively connected at their opposite ends to the device by means of which the opposite ends are spread apart and moved into engagement with the drum.

The fluid pressure actuated device comprises the opposed cylinders 4 and 5 of different diameters and the piston member 6 having the pistons 7 and 8 slidable within the cylinders 4 and 5, respectively, and forming therewith fluid receiving chambers of different cross sectional pressure areas. The cylinder 4 is of smaller internal diameter than the cylinder 5 and is operatively connected to the brake shoe 2 by the pivot pin 9 which extends through the web of the shoe and the bifurcations 10 on the closed end of the cylinder. The cylinder 5 is similarly operatively connected to the shoe 3 by the pivot pin 11 and the bifurcations 12 on the closed end of the cylinder. The piston member 6 is a unit in which the pistons 7 and 8 are integral and at opposite ends of the piston member. The piston member has the port 13 intermediate its ends and adapted to be connected by suitable tubing to the master cylinder of the motor vehicle. The piston member also has the separate passages 14 and 15 extending from the port 13 in opposite directions axially through the pistons 7 and 8 to the ends thereof and opening into the cylinders 4 and 5, respectively, for conducting fluid under pressure from the port to the chambers formed by the cylinders and their pistons. Suitable sealing means are provided between the pistons and their cylinders to prevent the escape of the braking fluid which, in the present instance is a braking liquid. The sealing means, as shown, comprises sealing rings located in annular grooves in the pistons and slidably engaging the walls of the cylinders.

To control the flow of fluid under pressure through the passages 14 and 15, there is the unit valve mechanism 16 carried by the piston member and comprising the valves 17 and 18. The valve 17 is a cylindrical member having an external diameter to slidably extend into the passage 14. The end portion of this passage is formed with the longitudinal flutes 19 which provide for the flow of fluid past the valve when in the position shown in Figure 2. The valve is provided with the sealing ring 20 located in an annular groove in the valve and adapted to engage the wall of the passage 14 inwardly beyond the flutes to close the passage. The valve is also provided with the annular flange 21 at its outer end for engaging the end of the piston 7 to limit the movement of the valve in an inward direction.

The valve 18 is cup-shaped and has a cylindrical outer wall of greater diameter than the valve 17 and the diameter is such that the valve is slideable within an enlarged portion 22 of the passage 15. The end part of the enlarged portion 22 of the passage 15 is formed with the longitudinal flutes 23 which provide for the flow of fluid past the valve when the sealing ring 24 of the valve is located over the flutes 23. In the position shown in Figure 2, the sealing ring 24 engages the solid part of the enlarged portion so that the valve 18 closes the passage 15. The valves 17 and 18 are connected by the rod 25 so that the two valves move in unison. The rod is preferably integral with the valve 18 and extends from the bottom of its cup and is threaded into the valve 17.

To normally hold the valve mechanism in a position such that the valve 17 opens the passage 14 and the valve 18 closes the passage 15, as shown in Figure 2, I have provided the coil spring 26 which at one end abuts the outer end of the valve 18 and at the other end abuts the stop 27 which rests against the split ring 28 seated in an interrupted annular groove formed in the lands 29 between which the flutes 23 are formed.

30 is a compression coil spring within the cylinder 4 of smaller diameter and abutting its closed end and the outer end of the piston 7 for resiliently returning the cylinder 5 and the piston member 6 to their off positions upon release of the pressure on the fluid. The arrangement is such that upon release of fluid pressure the cylinder 5 of larger diameter moves inwardly over the piston 8 until the closed end of the cylinder abuts the outer end of the piston so that the two are predeterminedly located with respect to each other. Since the cylinders 4 and 5 are carried by the brake shoes 2 and 3 and in turn carry the piston member, the adjustment of the brake by suitable means, such as eccentrics, to compensate for wear of the brake lining affects the position of the cylinder 4 relative to the piston member 6 only.

For the purpose of permitting the fluid in the cylinder 5 to escape through the port 13 after the fluid pressure actuated device has been operated, I have provided the ports 31 extending through the bottom of the cup-shaped valve 18, the partition 32 having a central port therethrough and the valve 33 for controlling this port. The partition is fixedly secured within the annular wall of the cup-shaped valve 18 and the valve 33 is located between the partition and the bottom of the cup and has the stem 34 extending through the port in the partition. 35 is a compression coil spring encircling the stem and abutting at one end the partition and at the other end the collar 36 which is secured to the end of the stem, the spring acting to resiliently hold the valve against the partition to close the port, but being yieldable during the return of the parts to their off positions to permit the flow of fluid through the port from the cylinder 5.

In operation and with the parts in their off positions, as shown in Figure 2, when fluid under pressure is forced through the port 13 and into the passages 14 and 15 it flows through the passage 14 only inasmuch as the valve 17 is in open position and the valve 18 is in closed position. Since the piston 8 abuts the closed outer end of the cylinder 5 and the coil spring exerts a predetermined pressure upon the valve mechanism 16 holding the valve 17 open and the valve 18 closed, the fluid moves the cylinder 4 outward-

ly along the piston 7 to spread apart the brake shoes 2 and 3 to take up all brake clearance and to move the brake shoes into engagement with the brake drum 1. At this time the pressure of fluid in the cylinder 4, the passage 14 and the port 13 has reached a predetermined point such that the fluid acting on the larger diametered valve 18 collapses the coil spring 26 and moves the valve mechanism. The sealing ring 24 of the valve 17 is located to pass completely over the flutes 23 and completely close the passage 14 before the sealing ring 24 of the valve 18 moves off the solid part of the enlarged portion 22 of the passage 15. As a result, fluid in the cylinder 4 is trapped before fluid flows to the cylinder 5 so that the cylinder 4 and the piston 7 act to hold the unit piston member 6 stationary with respect to the cylinder 4. Upon continued forcing of the fluid through the port 13, the unit valve mechanism continues to move until the sealing ring 24 of the valve 18 moves over the flutes 23 so that the fluid may flow into the cylinder 5 and cause this cylinder to move outwardly with respect to the piston 8, thereby compelling the brake shoes to more firmly engage the brake drum. It will be noted that the stop 21 of the valve may act upon the outer end of the piston 7 to limit this movement of the valve mechanism, if necessary. Upon relieving the fluid from pressure, the parts will be returned to their off positions by the coil springs 26 and 30 during which time the valve 33 will be moved to open position. As a result, the fluid within the cylinders 4 and 5 is returned to the port 13 and then to the master cylinder.

It will be seen that the construction is such that fluid can be forced to but one cylinder at any time since the valve mechanism closes either the one or the other of the passages leading to the cylinders. It will also be seen that the construction is such that the cylinder of smaller diameter will be first moved outwardly with respect to the piston member and then the cylinder of larger diameter will be moved outwardly with respect to the piston member so that the fluid pressure actuated device functions to apply the brake shoes in two separate stages and with a greater force during the second stage without increasing the pressure of the fluid entering the device.

What I claim as my invention is:

1. A fluid pressure actuated device comprising a unit piston member having pistons of different diameters, a port and passages extending in opposite directions from said port to the free ends of said pistons, cylinders within which said pistons are slideable, and valve mechanism for controlling said passages comprising a valve for controlling the passage extending to the free end of the piston of smaller diameter, said valve normally occupying an open position to place the cylinder of smaller diameter in communication with the port, said valve mechanism also comprising a second valve for controlling the passage extending to the free end of the piston of larger diameter, said second valve normally occupying a position closing said last mentioned passage, said valves being movable in unison and being relatively positioned so that said first mentioned valve is moved to closed position before said second valve is moved to open position.

2. A fluid pressure actuated device for actuating friction elements, said device comprising a unit piston member having pistons at its ends of different diameters, a port between its ends

and passages extending in opposite directions from said port to the free ends of said pistons, cylinders within which said pistons are slidable, said cylinders being operatively connected to the friction elements and carrying said unit piston member, and unit valve mechanism for controlling the flow of fluid through said passages, said unit valve mechanism being movable by the fluid to positions permitting the flow of fluid through said passages to one only of said cylinders at any time.

3. A fluid pressure actuated device comprising fluid receiving chambers of different cross-sectional pressure areas, separate ports for conducting fluid under pressure to each of said chambers; and unit valve mechanism normally opening the port to the chamber of smaller area and closing the port to the chamber of larger area, said unit valve mechanism moving successively, when the fluid attains a predetermined pressure, to positions which will first close the port to the chamber of smaller area, and subsequently open the port to the chamber of larger area.

4. A fluid pressure actuated device comprising fluid receiving chambers of different cross-sectional pressure areas, separate ports for conducting fluid under pressure to each of said chambers, and unit valve mechanism for controlling the flow of fluid through said ports to both of said chambers, said unit valve mechanism being movable, when the fluid attains an increased predetermined pressure, to positions which will close the port to the chamber of smaller cross-sectional pressure area before opening the port to the chamber of larger cross-sectional area.

5. A fluid pressure actuated device comprising fluid receiving chambers of different cross sectional pressure areas, different means for conducting fluid under pressure to each of said chambers, and unit valve mechanism for controlling the flow of fluid through said conducting means to both of said chambers, said unit valve mechanism comprising a valve for closing each of said conducting means, and means dependent upon the pressure of the fluid for moving said valves in timed relation whereby either occupies a closed position before the other occupies an open position.

6. A fluid pressure actuated device comprising a unit piston member having pistons of different diameters at its opposite ends, a port intermediate its ends, and passages extending from said port through said pistons to the ends thereof, cylinders within which said pistons are slidable, and spring means between the piston of smaller diameter and its cylinder for resiliently urging the piston of larger diameter toward its cylinder.

7. A fluid pressure actuated device for spreading apart a pair of brake shoes comprising opposed cylinders of different diameters operatively connected to said brake shoes, a unit piston member carried by said cylinders and having pistons at its opposite ends slidably extending within said cylinders, a port intermediate its ends and passages extending from said port through said pistons to said cylinders, a compression spring between the cylinder of smaller diameter and its piston for resiliently holding said piston member in predetermined relation to the cylinder of larger diameter, a unit valve mechanism comprising a valve for closing the passage leading to the cylinder of smaller diameter and a second valve for closing the passage leading to the cylinder of larger diameter, and a compression spring for resiliently holding said valve mechanism in a position with said first mentioned valve

10 in open position and said second valve in closed position.

20 8. A fluid pressure actuated device for spreading apart a pair of brake shoes comprising opposed cylinders of different diameters operatively connected to said brake shoes, a unit piston member carried by said cylinders and having pistons at its opposite ends slidably extending within said cylinders, a port intermediate its ends and passages extending from said port through said pistons to said cylinders, a compression spring between the cylinder of smaller diameter and its piston for resiliently holding said piston member in predetermined relation to the cylinder of larger diameter, a unit valve mechanism comprising a valve for closing the passage leading to the cylinder of smaller diameter and a second valve for closing the passage leading to the cylinder of larger diameter, and a compression spring for resiliently holding said valve mechanism in a position with said first mentioned valve

25 in open position and said second valve in closed position.

30 9. A fluid pressure actuated device for spreading apart a pair of brake shoes comprising opposed cylinders of different diameters operatively connected to said brake shoes, a unit piston member carried by said cylinders and having pistons at its opposite ends slidably extending within said cylinders, a port intermediate its ends and passages extending from said port through said pistons to said cylinders, a compression spring between the cylinder of smaller diameter and its piston for resiliently holding said piston member in predetermined relation to the cylinder of larger diameter, a unit valve mechanism comprising a valve for closing the passage leading to the cylinder of smaller diameter and a second valve for closing the passage leading to the cylinder of larger diameter, a compression spring for resiliently holding said valve mechanism in a position with said first mentioned valve in open position and said second valve in closed position, and means comprising a valve movable to open position during the return of said cylinders and piston member to off positions to provide for escape of the fluid from the cylinder of larger diameter.

35 10. A fluid pressure actuated device comprising fluid receiving chambers of different cross sectional pressure areas, means for conducting fluid under pressure to each of said chambers, and unit valve means for controlling the flow of fluid through said conducting means to both of said chambers, said unit valve means being operable upon movement in one direction to trap the fluid in one of said chambers prior to permitting the flow of fluid to the other of said chambers.
